Fig. 2.

Fig. 3.

Fig. 4.

Fig. 1 is a view in front elevation of a pipe coupling unit embodying our new design.

Fig. 2 is a top plan view of the same.

Fig. 3 is a side elevational view of the same.

Fig. 4 is a perspective view of a pair of pivoting lugs shown in Figs. 1, 2, and 3, but without the securing bolts.

The essential features of our design reside in the portions shown in full lines.

We claim:

The ornamental design for a pipe coupling unit, substantially as shown and described.
